UNITED STATES PATENT OFFICE.

EDWARD F. GEHRKENS, OF SCHENECTADY, NEW YORK, ASSIGNOR TO GENERAL ELECTRIC COMPANY, A CORPORATION OF NEW YORK.

MEANS FOR HEATING METALS.

970,488.

Specification of Letters Patent. Patented Sept. 20, 1910.

Application filed July 6, 1908. Serial No. 442,150.

To all whom it may concern:

Be it known that I, EDWARD F. GEHRKENS, a citizen of the United States, residing at Schenectady, county of Schenectady, State of New York, have invented certain new and useful Improvements in Means for Heating Metals, of which the following is a specification.

My invention relates to means for heating metal, and is particularly applicable to the heating of rails, car wheels and the like, a portion or portions of which it is desired to temper or harden.

According to my invention, I heat the metal rail or the like by generating current in a portion or portions of the metal by means of an electrical transformer, this portion or portions being in inductive relation to the primary of the transformer, another portion of the rail being in the magnetic circuit of the transformer.

In another aspect, my invention comprises the combination with a magnetic core having a winding thereon, of a piece of metal to be heated, a portion of which being in the magnetic circuit of said core, and another portion or portions placed in inductive relation to said winding.

Other features of my invention are pointed out with particularity in the claims annexed to and forming a part of this specification. For a better understanding of my invention, however, reference may be had to the following description taken in connection with the accompanying drawing, in which—

Figure 1 is a perspective view of a rail and a magnetic core arranged in accordance with my invention; Fig. 2 is a section on the line 2—2 of Fig. 3 looking in the direction of the arrows, and Fig. 3 is a view of a magnetic core and car wheel with parts broken away and in section, arranged in accordance with my invention.

Referring to Fig. 1 of the drawing, the tread portion 3 of the rail 4 is heated by current induced in it by the changing flux in the magnetic core 5. This core 5 is laminated and is wound with a coil of wire 6 to which alternating current is supplied from a suitable source by means of the leads 7. This coil of wire 6 acts as the primary of a transformer. The laminations of the core 5 do not form a complete magnetic cir-

cuit, but have a gap formed therein. The head 8 of the rail is placed in this gap and completes the magnetic circuit of the core. The tread portion 3, and the web 9' and flange 9 in parallel, are in inductive relation to the winding 6 and with the portions 10 and 11 of the rail form a link about the magnetic circuit of the core 5 and act as the secondary of the transformer. The current induced in the rail at some one instance flows in one direction through the tread portion 3, the portion 10, the web 9' and flange 9 in parallel, and the portion 11 of the rail, and the next instance in the opposite direction in these portions. Since the tread portion 3, which is in inductive relation to the winding 6 and the core 5, is of small cross-section, as compared with the combined cross-section of the web and flange, the current density will be much greater in the tread portion and it will become heated while the web and flange will remain comparatively cool. When it reaches the proper degree of heat, the core 5 is removed and the rail tempered, or any other operation performed that is desired.

By placing the core so that the tread portion and the web and flange portion, which are in inductive relation to the winding and core, are of equal cross-section, the whole rail may be equally heated, the portion which is in the magnetic circuit of the core being of relatively small cross-section and heated by eddy currents and by conduction. By making the core 5 of great length, a whole section of rail may be heated.

Referring to Figs. 2 and 3, the portion or portions 12 comprising the rim of the car wheel 13 are placed in inductive relation to the coils 14 of the magnetic core 15. This core 15 is built up of laminations of involute cross-section closely packed to form a hollow cylinder, as disclosed in the application of Walter C. Fish, No. 351,968, filed January 12, 1907, for magnetic cores for electric apparatus. The coils 14 are placed in recesses in the core. The core is divided at 16 and has a gap at 17, so that it may be placed about the wheel 13, the portion 18 of the wheel completing the magnetic circuit of the core 15. The rim 12, therefore, forms a link about the magnetic circuit and has current induced in it first in one direction and then in the other. This heats it

and when it reaches the proper temperature the core is removed and the rim tempered, or operated upon as desired.

What I claim as new and desire to secure by Letters Patent of the United States, is:

1. In combination, a magnetic core having a winding thereon, and a piece of metal, a portion of which is in the magnetic circuit of said core, and a portion or portions to be heated in inductive relation to said winding.

2. In combination, a magnetic core having a gap therein, and a winding thereon, a piece of magnetic material, a portion of which is in said gap and completes the magnetic circuit of said core, and a portion or portions in inductive relation to said winding.

3. In combination, a magnetic core having a winding thereon, and a piece of metal, a portion of which is in the magnetic circuit of said core, and another portion or

portions which form a link about the magnetic circuit of said core.

4. In combination, a magnetic core having a gap therein, a winding on said core, and a piece of metal, a portion of which fits in said gap, and another portion or portions which forms a link about the magnetic circuit of said core.

5. In combination, a magnetic core having a gap therein, a winding on said core, and a disk-shaped piece of magnetic metal, a portion of which fits in said gap and completes the magnetic circuit of said core, and another portion or portions which forms a link about the magnetic circuit of said core.

In witness whereof, I have hereunto set my hand this 3rd day of July, 1908.

EDWARD F. GEHRKENS.
